Centa Isermann, nee Cossman, Tucson, Ariz.

Application January 31, 1948, Serial No. 144,204

Term of patent 7 years

(Cl. D58—12.6)

To all whom it may concern:

Be it known that I, Centa Isermann, nee Cossman, a citizen of the United States of America, residing at Tucson, in the county of Pima and State of Arizona, have invented a new, original, and ornamental Design for a Bottled Perfume Package, of which the following is a specification, reference being had to the accompanying drawing, forming part thereof.

In the drawing

Fig. 1 is a front perspective view of a bottled perfume package, showing my new design;

Fig. 2 is a front elevational view thereof with parts being shown broken away.

I claim:

The ornamental design for a bottled perfume package, as shown.

CENTA ISERMANN, NEE COSSMAN.
